US0D1027979S

(12) **United States Design Patent** (10) **Patent No.:** **US D1,027,979 S**
Ryu (45) **Date of Patent:** **** May 21, 2024**

(54) **DISPLAY SCREEN OR PORTION THEREOF WITH GRAPHICAL USER INTERFACE**

(71) Applicant: **INTUIT INC.**, Mountain View, CA (US)

(72) Inventor: **Jung Yeon Ryu**, Mountain View, CA (US)

(73) Assignee: **INTUIT INC.**, Mountain View, CA (US)

(**) Term: **15 Years**

(21) Appl. No.: **29/833,457**

(22) Filed: **Apr. 4, 2022**

Related U.S. Application Data

(62) Division of application No. 29/766,923, filed on Jan. 19, 2021, now Pat. No. Des. 947,894, which is a division of application No. 29/645,455, filed on Apr. 26, 2018, now abandoned.

(57) **CLAIM**

The ornamental design for a display screen or portion thereof with graphical user interface, as shown and described.

DESCRIPTION

FIG. 1 is a front view of a display screen or portion thereof with graphical user interface showing our new design; FIG. 2 is a front view of a second embodiment thereof; and, FIG. 3 is a front view of a third embodiment thereof. The outermost broken lines in the Figures show a display screen or portion thereof and form no part of the claimed design. Other broken lines show portions of the graphical user interface and form no part of the claimed design. The text, number, symbol, and otherwise images shown in broken lines in the Figures are for illustrative purposes only and form no part of the claimed design.

1 Claim, 1 Drawing Sheet
